UNITED STATES PATENT OFFICE.

RICHARD GRIFFITH, OF AKRON, OHIO, ASSIGNOR TO MILLER RUBBER CO., OF AKRON,
OHIO, A CORPORATION OF OHIO.

TOY BALLOON.

1,158,206.

Specification of Letters Patent. Patented Oct. 26, 1915.

Application filed March 10, 1915. Serial No. 13,403.

To all whom it may concern:

Be it known that I, RICHARD GRIFFITH, a citizen of the United States, residing at Akron, in the county of Summit and State 5 of Ohio, have invented certain new and useful Improvements in Toy Balloons, of which the following is a specification.

The present invention relates to toy balloons and pertains more particularly to that 10 type of balloons which is inflated by blowing air through a mouth-piece and can be deflated at will by allowing the air to escape from the same.

The principal object of the invention consists in providing a balloon of this type 15 with an improved form of valve mechanism adapted to be inserted and retained in the mouth-piece.

The invention further consists in providing 20 a novel form of valve constructed of material which will be sufficiently light and at the same time of simple construction.

With these and other objects in view, the invention consists in the construction and 25 combination of parts more fully set forth hereinafter in the specification, illustrated in the accompanying drawings and pointed out in the appended claims.

In the drawings: Figure 1 is a longitudinal section through a toy balloon, with the improved valve inserted in the neck thereof. Fig. 2 is an enlarged bottom plan of the valve alone and, Fig. 3 is an enlarged sectional view of the same at right-angles to 35 Fig. 1.

Referring to the drawings, the balloon comprises a hollow body B of thin rubber of pure quality and extreme elasticity, which will permit of its being inflated and 40 expanded to many times its normal size.

The balloon B in its normal deflated condition is preferably of elliptical form and is provided with a tubular neck or mouth-piece C extending from one end and in substantial alinement with its longest axis as 45 shown in Fig. 1. The valve mechanism which is adapted to be inserted in the neck-piece C comprises a metal disk 1 of aluminum or other sufficiently light metal and is provided with a centrally located circular opening 2. The disk 1 is formed with a small integral flange 1^a extending at right-angles thereto.

A small flap 3 of rubber or other suitable 50 elastic material is provided and is adapted

to be clamped by a lug 4 to the inner side of the disk 1. This flap 3 is of circular shape and being attached at only one point to the inner side of the disk 1, it acts as a valve to completely close the aperture 2 60 when the balloon is inflated. The outer end of the neck-piece C of the balloon is provided with a reinforcing ring c and when the disk valve mechanism has been inserted into the end of the neck-piece C, the reinforcing ring c which is elastic encircles the outer edge or periphery of the disk 1 and serves to firmly hold the valve disk or plate 1 securely in place. In order to deflate the balloon, it is only necessary to slightly dislodge the flap 3 from the aperture 2 and this can be easily done by means of a match stem, pencil point, or similar article.

The disk 1 is not permanently attached by cement to the sides of the neck-piece C but 75 is merely retained in position by the elastic nature of the neck-piece C and the reinforcing ring c. By having the valve disk 1 provided with an inturned edge or flange 1^a 80 an air-tight valve is provided on the inside of the balloon neck and the necessity of cementing the valve is thus obviated.

It will be understood that the rubber flap or valve 3 is considerably larger than the hole or aperture 2 and hence the pressure 85 exerted by the air within the balloon when it is inflated tends to maintain equal tension on the inner surface of this flap, thus insuring a completely air-tight valve.

A valve mechanism constructed in accordance with the present invention possesses the further advantages of being extremely light in weight, simple in construction and easy to insert or remove in or from the mouth-piece of the balloon.

What I claim is:

1. A toy balloon having a tubular neck or mouth-piece integral therewith, a disk member adapted to be removably inserted and retained in said neck and a self-closing valve carried by said member, substantially as described.

2. A toy balloon having a tubular neck or mouth-piece integral therewith, a metal disk member adapted to be removably inserted and retained in said neck and a flexible self-closing valve carried by said disk member, substantially as described.

3. A toy balloon having a tubular neck or mouth-piece integral therewith, a perfo-

rated disk formed of aluminum adapted to be inserted in said neck and a self-closing flap valve carried on the inner side of said disk, substantially as described.

- 5 4. A toy balloon having a tubular neck or mouth-piece integral therewith, a perforated metal disk having an inturned flange, said disk adapted to be inserted in the outer end of said neck, and a rubber disk flap

valve secured to the inner side of said disk, 10 substantially as described.

In testimony whereof I affix my signature in presence of two witnesses.

RICHARD GRIFFITH.
